[57] CLAIM

The ornamental design for a bicycle security unit or the like, as shown and described.

DESCRIPTION

FIG. 1 is a perspective view of a bicycle security unit or the like showing my new design;

FIG. 2 is a front elevational view thereof;

FIG. 3 is a side elevational view thereof, the opposite side being a mirror image of that shown;

FIG. 4 is a top plan view thereof; and

FIG. 5 is a bottom plan view thereof.

The broken-line showing of portions of a bicycle and post in the views is for illustrative purposes only and forms no part of the claimed design.
